CYLINDER LOCK

William E. Hamilton, Evanston, Ill., assignor to
Dudley Lock Corporation, Chicago, Ill., a corporation of Illinois

Application April 30, 1940, Serial No. 332,578

8 Claims. (Cl. 70—364)

This invention relates to a cylinder lock of the type in which a plurality of tumblers are slidably mounted in a cylinder and project therefrom into grooves or notches in a casing in which the cylinder can rotate when the tumblers are withdrawn within it and out of engagement with such grooves or notches. The proper key for a particular lock of this type operates to so withdraw the tumblers, usually in opposition to springs which urge them into engagement with the casing grooves or notches. The tumblers may be formed with notches or cut-away portions sufficient to accommodate the springs in the same channels in which the tumblers slide; but in that case special abutment means must be provided in the channels against which the springs may react. It is quite common practice to drive individual pins through the body of the cylinder to project into these channels and serve as abutments for the springs.

One object of the present invention is to provide a substitute for these individual pins.

Another object is to arrange the substitute abutment means in a form which is simple and convenient for assembly in the lock cylinder.

A further object is to provide means for securely fastening such abutment members in position with a relatively simple operation.

Other objects of the invention will appear as the description proceeds. The invention consists of various features and elements in combination, as herein shown and described and as indicated by the claims.

In the drawing:

Figure 1 is a perspective view of a pronged, stamped member providing spring abutments in accordance with this invention.

Figure 2 is a face view of the same.

Figure 3 is an end elevation of the member.

Figure 4 is an inside face view of one-half of a lock cylinder with a portion of the tumblers and springs assembled therein and with the pronged stop member of this invention in place.

Figure 5 is an outside elevational view of the cylinder section showing the means of securing the pronged stop device in place.

Figure 6 is a transverse section of an assembled cylinder lock employing this invention, section being taken substantially at the plane indicated by line 6—6 on Figure 5.

Referring first to Figure 6, it may be understood that the type of lock to which this invention is applied includes an outer casing 1 which may be cylindrical in form and within which there is rotatably mounted a lock cylinder comprising two halves 2, 2 usually made from blocks of solid metal, such as brass, with channels 3 milled therein to accommodate slidable tumbler members 4. In the form shown the lock includes

center plates 5, 5 which are secured between the two halves 2, 2 of the cylinder, and against which the tumblers 4 slide in their channels 3. As shown in Figure 6, one of the tumblers 4 projects into a groove 6 of the casing 1, and the other tumbler projects into a similar groove 7 for locking the cylinder against rotation. But insertion of the proper key between the center plates 5, 5 serves to withdraw the tumblers from the grooves 6 and 7, so that they are contained wholly within the dimensions of the cylinder, thus permitting the latter to be rotated for operating the lock. Each of the tumblers 4 is provided with a spring 8 which is accommodated in a cut-out portion 9 formed in the rear edge of the tumbler—that is, the edge away from the key slot. The bottom 10 of each of the channels 3 is straight from end to end of the channel, so that portions of the tumbler slide against the straight bottom wall of the channel.

The cylinder section 2 is drilled or otherwise formed with openings 11, each extending outwardly from the bottom 10 of one of the channels 3 to the outer surface of the cylinder, and each 15 of these openings is occupied by a member which projects into the channel 3 to serve as an abutment for the spring 9. Instead of employing individual abutment members, such as pins, driven into the openings 11, I form these members as prongs 12 of a unitary structure which includes a back plate 13, said plate being of approximately the same length as the cylinder section 2, and having the prongs 12 bent to extend at right angles from it, as seen in Figure 1. These prongs 20 are spaced from each other so as to register simultaneously with all the openings 11 in one of the cylinder halves 2 when the plate is applied to the outer surface of the cylinder and pressed inwardly. Preferably, the prongs 12 are tapered so that some force must be employed to press them "home" through the openings 11, and in this final position the prongs project into the several guide channels 3 in which the tumblers 4 are slidably carried. The outer or curved face of each cylinder half 2 is formed with a shallow channel 14 of substantially the same width as the back plate 13 and of a depth just sufficient to accommodate its thickness. Thus, when the unit comprising the back plate 13 and prongs 12 has been forced into the cylinder 2 until the back plate lies flatly against the bottom of the channel 14, and the prongs 12 project into the channels 3, it is a simple matter to secure the unit in this position by slightly upsetting the back plate 13 so as to widen it sufficiently to make it fit tightly between the side walls of the channel 14. This operation can be performed by means of any tool of tapered formation, such as a center punch or cold chisel, and is commonly known as "staking."

Imprints of such a tool of the character of a cold chisel are shown at 15 in Figure 5, from which it will be readily recognized that this treatment will spread the plate 13 sufficiently to make it fit tightly and permanently in the channel 14, particularly since the individual prongs 12, being of tapered formation, are also tightly wedged in the respective openings 11 in the cylinder section 2.

When each of the cylinder halves 2, 2 has been provided with one of these unitary prong members, it is then ready for assembly of the springs 9 and tumblers 4 in their proper arrangement in the channels 3, after which the two cylinder halves 2, 2 may be secured together with the center plates 5, 5 in position as located by bosses 16 projecting from the flat faces of the sections 2, 2.

Thus it will be seen that the employment of the unitary member comprising a back plate 13 and prongs 12 will greatly facilitate the assembly of the lock, in addition to saving a considerable amount of time heretofore employed in measuring and cutting and setting individual stop pins for the several springs 8. If the openings 11 in the cylindrical body portion 2 be made round in cross-section, as shown, and the prongs 12 be of rectangular cross-section, as shown, it will not require any great force to drive the wedge-shaped prongs into these holes, but their edges will be sufficiently deformed in this operation to hold them tightly in place, independently of the tightening of the back plate 13 between the walls of the channel 14. While there is shown and described herein certain specific structure embodying the invention, it will be manifest to those skilled in the art that various modifications and rearrangements of the parts may be made without departing from the spirit and scope of the invention, and that the same is not limited to the particular form herein shown and described, except in so far as indicated by the appended claims.

I claim as my invention:

1. In combination, a lock cylinder having a plurality of channels for the tumblers and their individual springs, with a transversely disposed opening extending from the bottom of each channel to the outer surface of the cylinder, and a unitary member comprising a back plate and a plurality of prongs projecting transversely from it in position to fit into the respective openings at one side of the cylinder, said prongs being dimensioned to protrude into the channels to serve as stops for the tumbler springs.

2. In combination, a lock cylinder having a plurality of channels for the tumblers and their individual springs, with a transversely disposed opening extending from the bottom of each channel to the outer surface of the cylinder, and a unitary member comprising a back plate and a plurality of prongs projecting transversely from it in position to fit into the respective openings at one side of the cylinder, said prongs being dimensioned to protrude into the channels to serve as stops for the tumbler springs, and the cylinder having a channel formed in its outer cylindrical surface to accommodate the back plate.

3. In combination, a lock cylinder having a plurality of channels for the tumblers and their individual springs, with a transversely disposed opening extending from the bottom of each channel to the outer surface of the cylinder, and

a unitary member comprising a back plate with a plurality of tapered prongs projecting transversely from it in position to register with the respective openings at one side of the cylinder, the portions of said prongs adjacent the back plate being slightly wider than the openings, whereby they are wedged tightly therein when the back plate is forced against the cylinder, said prongs being dimensioned to protrude into the channels to serve as stops for the tumbler springs.

4. In combination, a lock body having a plurality of guideways for the tumblers and their individual springs, with a transversely disposed hole intersecting each guideway and extending to the outer surface of said body, and a unitary member comprising a back plate with a plurality of prongs projecting transversely from it in position to register with the respective holes at one side of the body, said holes being cylindrical in form and said prongs being of rectangular cross-section dimensioned to be forced into the holes and to protrude into the guideways to serve as stops for the tumbler springs.

5. In the combination defined in claim 4, said prongs being tapered converging outwardly from the back plate whereby their edges are adapted to be deformed when the prongs are wedged into the holes by forcing the back plate against the body member of the lock.

6. In combination, a lock cylinder having a plurality of guideways for the tumblers and their individual springs, with a transversely disposed opening extending from each guideway to the outer surface of the cylinder, and a unitary member comprising a back plate and a plurality of prongs projecting transversely from it in position to fit into the respective openings at one side of the cylinder, said cylinder having a channel in its outer surface formed to accommodate the back plate and the prongs being dimensioned to protrude into the guideways to serve as stops for the tumbler springs when the back plate is disposed in said channel, the material of the back plate being upset to fit the plate tightly between the side walls of said channel.

7. In combination, a lock body member having a plurality of guideways for the lock tumblers and their individual springs, with a transversely disposed opening intersecting each guideway and extending to the outer surface of said body member, and a unitary member comprising a back plate with a plurality of prongs projecting transversely from it in position to fit into the respective openings at one side of the body member, said prongs being dimensioned to protrude into the guideways to serve as stops for the tumbler springs.

8. A unitary part to provide stops for a lock body having a plurality of guideways for the lock tumblers with transversely disposed holes intersecting the respective guideways and extending to the outer surface of such body member, said part comprising a back plate with a plurality of tapered prongs extending from two opposite edges of the plate at spaced intervals and in staggered relation to each other, said prongs being substantially perpendicular to the plate and parallel to each other and being tapered converging outwardly from the back plate, whereby their edges are adapted to be deformed when the prongs are wedged into the holes by forcing the back plate toward the outer surface of the body member.

WILLIAM E. HAMILTON.
